UNITED STATES PATENT OFFICE.

KENNETH J. UNWIN, OF SHREWSBURY, MASSACHUSETTS, ASSIGNOR TO CROMPTON & KNOWLES LOOM WORKS, OF WORCESTER, MASSACHUSETTS, A CORPORATION OF MASSACHUSETTS.

FINGER SEPARATING AND LEVELING DEVICE FOR LOOM DOBBIES.

Application filed August 24, 1926. Serial No. 131,291.

This invention relates to improvements in loom dobbies and leveling devices therefor and it is the principal object of the invention to provide a combined leveling and separating element to cooperate with dobbie fingers such as may be formed from sheet metal.

Loom dobbies are usually provided with a pattern chain having spaced pegs which lift so-called fingers when the harnesses corresponding thereto are to be raised. The fingers are narrow and in order to provide for proper registry with the pegs it is necessary to equip the dobbie with some form of comb which will space the fingers accurately with respect to the pegs. This is usually accomplished by means of a comb having upright wires which lie between reduced parts of the fingers.

In certain picking out operations it is desirable to level all the harnesses and this may be done by raising all the fingers so that the hooks will be down, a condition which, as understood by those familiar with dobbies, corresponds to a leveling up of the harnesses. In order to permit the dobbie fingers to be made of stamped metal without the customary thin ends and also allow for the leveling action I provide an oscillatable leveling element having dents which align with alternate fingers to separate the intermediate fingers.

It is a further object of my invention to provide means for properly aligning the fingers when the leveling device is rotated for the purpose of raising the fingers.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a vertical central section through a dobbie having my invention applied thereto,

Fig. 2 is an enlarged detail horizontal section on line 2—2 of Fig. 1,

Fig. 3 is an enlarged vertical section through the lower portion of one of the fingers taken on line 3—3 of Fig. 1,

Figs. 4 and 5 are elevations of the two types of fingers employed for the lower and upper hooks, respectively,

Fig. 6 is a fragmentary view similar to a

portion of Fig. 1 but showing the leveling device in finger raising position,

Fig. 7 is a detail end elevation of a portion of the dobbie looking in the direction of arrow 7, Fig. 1, and

Fig. 8 is a perspective view of the leveling device.

Referring to the drawings, it will be seen that I have provided a dobbie frame D and a number of harness jacks one of which is indicated at 20. Said jacks move pivotally about a rod 21 fixed in the frame D and are connected as at 22 to dobbie back levers 23. Each lever 23 is connected at the upper part thereof to a hook 24 to cooperate with upper reciprocating knife 25 while the lower end of each lever 23 has a hook 26 to cooperate with lower reciprocating knife 27. The knives reciprocate horizontally in opposite directions by mechanism not shown but well understood. Movement of the levers 23 to the left as shown in Fig. 1 is limited by bars 28 and combs 29 space and guide the hooks. The pattern mechanism for controlling the harness levers comprises a cylinder 30 mounted on a shaft 31 and cooperating with a series of chain bars 32 each of which is provided with pegs 33 arranged in such order as will produce the desired weave. The matter thus far described is usual in dobbie construction and forms no part of my present invention.

The pegs 33 cooperate with a set of dobbie fingers made up of two distinct types of fingers indicated at 40 and 41, as shown in Figs. 4 and 5, respectively. Each finger 40 is provided at the right hand end thereof with an enlargement 42 to add weight and is provided at the other end thereof with an upwardly curved tail 43 positioned for direct engagement with one or another of the lower hooks 26.

Each finger 41 is provided with a tail 44 extending substantially straight and horizontally from the finger and having supporting contact with the lower end of one of a set of lifter rods 45 for the upper hooks 24. Both types of fingers are provided with notches 46 which receive a supporting rod 47 fixed in the dobbie frame and upward displacement of the fingers may be prevented by a wire 48 lying immediately above the fingers and extending substantially parallel to the rod 47.

The fingers 40 as shown in Fig. 4 are pro-

vided with a cut-away portion 49 while the corresponding portion of the other type of finger 41 as shown in Fig. 5 is left solid and is not cut away, the purpose of the cut-away 5 portions 49 being to receive guides to be described hereinafter. The fingers as already described may be similar to those shown in co-pending application Ser. No. 131,290 filed by Holmes.

10 In carrying my invention into effect I provide each of the fingers with a small notch 50 on the under side thereof and further provide a leveling device L formed in part with a substantially horizontal blade 15 51 to cooperate with the notches 50. As shown in Fig. 8 said blade is provided with a number of slots 52 and teeth 53 lying between the slots. The leveling device is provided with a pair of bearing portions 54 20 the upper and lower surfaces of which are horizontal as shown in Figs. 1 and 8 to receive the downward pressure of that part of the fingers lying immediately to the left of the notches 50. The weight of the fingers, 25 co-acting with the flat surface of the leveling device, tends to hold the latter in proper position. The leveling device is provided with depending handles 55 which cooperate with supporting bearings 56 held 30 to the frame D, said bearings and handles preventing endwise motion of the leveling device to hold the same in proper alignment with the fingers.

Said leveling device as shown in Figs. 35 1, 6, 7, and 8 is further provided with a plurality of spaced dents 57 so proportioned that when in the normal position indicated in Fig. 1 said dents will lie in the cut-away portions 49 of the fingers 40 and will serve 40 to space the fingers 41 by having guiding contact with the extreme lower right hand ends of said fingers as viewed in Fig. 1.

Under normal conditions the cylinder 30 will rotate and by means of the pegs 33 45 will cause a raising and lowering of the fingers 40 and 41 in the order necessary to produce the desired weave, said fingers 41 being guided in their vertical motion by the dents 57 and the fingers 40 being positioned 50 by the fingers 41. When it is desired to level the harnesses the leveling element L will be moved from the position shown in Fig. 1 to that indicated in Fig. 6, the fingers 41 being received by the slots 52 of the 55 blade 51 and the teeth 53 engaging the fingers 40. In order to facilitate this action a portion of each of the fingers 40 lying between the notch 50 and the run for the peg 33 is removed as indicated at 58 so that the 60 fingers 41 may be received by the slots 52 before the fingers 40 start to rise. As indicated in Fig. 6 the dents 57 pass entirely out of the cut-away portions 49 and out of alignment with any part of the fingers but 65 this does not happen until after the fingers

41 have been received by the slots 52 and therefore improper alignment of the fingers is prevented even though the dents 57 are not operatively positioned to space the fingers. By continued turning movement of 70 the leveler L the teeth 53 and that part of the blade located at the bottom of the slots 52 will be received by the small notches 50 of both types of blades so that the leveling device will be held in the position indicated 75 in Fig. 6 by the weight of the fingers.

When the fingers are returned to normal position the leveling device can be moved out of the notches 50 by a slight pressure on one or another of the handles 55 and all of 80 the fingers will be properly aligned by the slots 52 until the dents 57 enter the cut-away portions 49 between the fingers 41. In this way the fingers are kept properly aligned during the leveling action so that 85 the dents 57 may return to their proper position without interference by the fingers 41. Both types of fingers are provided with concave runs 59 to aid in maintaining proper registry with the pattern chain pegs. 90

From the foregoing it will be seen that I have provided a leveling device for a dobby equipped with fingers of uniform thickness wherein the leveling element is provided with spaced dents so placed as to align the 95 fingers of the dobby with the pattern mechanism. It will further be seen that the leveling element is so constructed that when the dents move out of relation with respect to the fingers auxiliary or additional spacing means come into action to retain the proper alignment of the fingers. It will further be seen that the leveling device, being provided with flat upper and lower surfaces, cooperates with the fingers so that the weight of the latter tends to hold the dents in proper position with respect to the fingers. Furthermore, said leveling device supports the outer ends of the fingers, thus dispensing with the usual bar and pegs. 100 105 110

Having thus described my invention it will be apparent that changes and modifications may be made therein by those skilled in the art without departing from the spirit and scope of the invention, and I do not wish to be limited to the details herein disclosed but what I claim is:

1. In a loom dobby, a set of dobby fingers, a leveling element for the dobby to engage said fingers during the leveling operation, and means carried by the leveling element to space the fingers.

2. In a loom dobby having harness levers and pattern mechanism and a set of dobby fingers, alternate fingers being cut away at 120 one portion thereof and the intermediate fingers being solid at the corresponding portions, a leveling element having a portion normally out of engagement with all the fingers and having dents to enter the cut- 125 130

away portions of the alternate fingers to guide the intermediate fingers, the aforesaid portion of the element being movable into engagement with the fingers to raise all of 5 said fingers to level the dobby.

3. In a loom dobby having harness levers and pattern mechanism and a set of dobby fingers, alternate fingers being cut away at one portion thereof and the intermediate 10 fingers being solid at the corresponding portions, a leveling element having a portion normally out of engagement with all the fingers and having dents to enter the cut-away portions of the alternate fingers to 15 guide the intermediate fingers, the aforesaid portion of the element being movable into engagement with the fingers to raise all of said fingers to level the dobby, said portion 20 of the leveling element being formed to separate and guide the fingers during the leveling operation.

4. In a loom dobby having harness levers and pattern mechanism and a set of dobby fingers, alternate fingers being cut away at one portion thereof and the intermediate 25 fingers being solid at the corresponding portions, a leveling element having a portion normally out of engagement with all the fingers and having dents to enter the cut-away 30 portions of the alternate fingers to guide the intermediate fingers, the aforesaid portion of the element being movable into engagement with the fingers to raise all of said fingers to level the dobby.

5. In a loom dobby having harness levers and pattern mechanism and a set of dobby fingers, alternate fingers being cut away at one portion thereof and the intermediate 40 fingers being solid at the corresponding portions, a leveling element to support the fingers and movable to raise all of said 45 fingers and having spaced dents rigid therewith to enter the cut-away portions of the alternate fingers.

6. In a loom dobby having harness levers and pattern mechanism and a set of dobby fingers, alternate fingers being cut away at one portion thereof and the intermediate 50 fingers being solid at the corresponding portions, a leveling element having two sets of finger separating members, one set being operative during the normal operation of the dobby and the other set being operative during the leveling operation of 55 the dobby.

7. In a loom dobby having harness levers and pattern mechanism and a set of dobby fingers, alternate fingers being cut away at one portion thereof and the intermediate 60 fingers being solid at the corresponding portions, a leveling element having two sets of finger separating members, one set being operative during the normal operation of the dobby and the other set being operative 65 during the leveling operation of the dobby,

both sets of members being positioned to separate the fingers when the latter are passing from normal to leveling position, whereby one set of members holds the fingers aligned until the other set can be operatively related to the fingers to space the same in proper alignment. 70

8. In a loom dobby having harness levers and pattern mechanism and a set of dobby fingers, alternate fingers being cut away at 75 one portion thereof and the intermediate fingers being solid at the corresponding portions, a leveling element having two sets of fingers separating elements, one set operatively related to the fingers during the 80 normal operation of the dobby and the other set operatively related to the fingers when the dobby is being leveled, each set of fingers being movable out of guiding relation with respect to the fingers and each set 85 effective when being moved out of guiding relation to guide the fingers until the other set comes into guiding relation with respect to the fingers.

9. In a loom dobby having harness levers 90 and pattern mechanism and a set of dobby fingers, alternate fingers being cut away at one portion thereof and the intermediate 95 fingers being solid at the corresponding portions, a leveling device having finger separating members to enter the cut-away parts of the alternate fingers, and a blade formed with the leveling element to engage the fingers as the element is moved to leveling position, said blade entering notches formed 100 on the under sides of all the fingers to hold said fingers in raised position.

10. In a loom dobby having harness levers and pattern mechanism and a set of dobby fingers, alternate fingers being cut away at 105 one portion thereof and the intermediate fingers being solid at the corresponding portions, a leveling device having finger separating members to enter the cut-away parts 110 of the alternate fingers, and a blade formed with the leveling element to engage the fingers as the element is moved to leveling position, said blade entering notches formed on the under sides of all the fingers to hold said fingers in raised position, that portion of the 115 fingers with the cut-away parts which cooperates with the blade being relatively higher than the corresponding portions of the other fingers.

11. In a loom dobby, a set of fingers, a leveling element to support a part of each of the fingers, and bearings for the element, that part of the element on which the fingers rest being substantially flat so that the weight of 120 said fingers will hold the leveling device 125 normally in a position inoperative to level the dobby.

12. In a loom dobby, a set of dobby fingers, a leveling element to support a part of each of the fingers, and bearings for the ele- 130

ment, that part of the element on which the fingers rest being substantially flat so that the weight of said fingers will hold the leveling device normally in a position inoperative to level the dobby, those parts of the element which rest on the bearings being also substantially flat.

13. A leveling element for a dobby having a set of fingers, alternate fingers of which 10 are provided with cut-away portions, said element having a set of dents to enter the cut-away portions of the alternate fingers and said element having another portion movable into engagement with all the fingers 15 to raise the same when the dobby is to be leveled.

14. A leveling element for a dobby having a set of fingers, alternate fingers of which are provided with cut-away portions, said 20 element having a set of dents to enter the cut-away portions of the alternate fingers and said element having another portion movable into engagement with all the fingers to raise the same when the dobby is to be 25 leveled, said element having bearing portions about which the same may be rotated to move the leveling portion thereof into engagement with the fingers.

15. A leveling element for a dobby having 30 a set of fingers, alternate fingers of which are provided with cut-away portions, said element having a set of dents to enter the cut-away portions of the alternate fingers

and said element having another portion movable into engagement with all the fingers 35 to raise the same when the dobby is to be leveled, said element having bearing portions about which the same may be rotated to move the leveling portion thereof into engagement with the fingers and the dents 40 out of operative relation with respect to the fingers.

16. A leveling element for a dobby having a set of fingers, alternate fingers of which are provided with cut-away portions, said 45 element having a set of dents to enter the cut-away portions of the alternate fingers and said element having another portion movable into engagement with all the fingers to raise the same when the dobby is to be 50 leveled, said element having bearing portions about which the same may be rotated to move the leveling portion thereof into engagement with the fingers, the upper portion of the 55 bearings being flat to receive the downward pressure of the fingers.

17. A leveling element for a loom dobby having a set of dobby fingers, said element having a portion to engage and raise the fingers during the leveling operation and said 60 element also having members to space the fingers during the normal operation of the dobby.

In testimony whereof I have hereunto affixed my signature.

KENNETH J. UNWIN.
